UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 21,772, dated August 9, 1892.

Application filed April 21, 1892. Serial No. 430,130. Term of patent 14 years.

To all whom it may concern:

Be it known that I, GEORGE H. BABCOCK, a citizen of the United States, residing at Plainfield, in the county of Union and State of New Jersey, have invented and produced a new and original Design for a Roofing or Sheathing Tile, of which the following is a specification, reference being had to the accompanying drawings, forming a part thereof.

10 My design relates to clay or other tiles in which ornamental architectural effects are produced by the contour or by the surface decoration of the tile in raised figures.

The design consists in a panel of approximately octagonal form and raised extension of circular form of smaller size than the panel and arranged with respect to the panel to cover its apex.

Figure 1 is an enlarged plan view of the tile or panel, and Fig. 2 a central longitudinal section of the same on the dotted line, Fig. 2.

The panel B has a substantially plane surface and is herein termed "octagonal" with reference to its essential number of sides. The surface of the circular part C stands above 25 the surface of the panel, being raised, and is of convex form. The upper part of the panel B is provided with an upturned flange e at its periphery, while the lower part is provided with a downturned flange f, which extends 30 (f' f'') around the peripheral part of the cover C continuous from the periphery of the panel B.

What I claim is—

The design for a sheathing or roofing tile, as herein shown and described.

GEO. H. BABCOCK.
